UNITED STATES PATENT OFFICE

170,196

CUP HOOK

Otto Gries, New Rochelle, N. Y.

Application March 16, 1953, Serial No. 24,045

Term of patent 14 years

(Cl. D54—2)

To all whom it may concern:

Be it known that I, Otto Gries, a citizen of the United States, residing at New Rochelle, State of New York, have invented a new, original, and ornamental Design for Cup Hooks, of which the following is a specification, reference being had to the accompanying drawing, forming a part hereof.

Fig. 1 is a side elevational view of a cup hook showing my new design.

Fig. 2 is an edge elevational view thereof looking at the right of Fig. 1; and

Fig. 3 is a bottom plan view.

I claim:

The ornamental design for a cup hook, as shown.

OTTO GRIES.
